UNITED STATES PATENT OFFICE.

FREDERICK C. HAZEN, OF LOS ANGELES, CALIFORNIA.

DESIGN FOR A CLOTHES-PIN.

SPECIFICATION forming part of Design No. 28,693, dated May 24, 1898.

Application filed August 30, 1897. Serial No. 650,058. Term of patent 14 years.

To all whom it may concern:

Be it known that I, FREDERICK C. HAZEN, a citizen of the United States, residing at Los Angeles, in the county of Los Angeles and State of California, have invented and produced a new and original Design for Clothes-Pins, of which the following is a specification, reference being had to the accompanying drawing, forming a part thereof, in which the figure represents a side elevation of a clothes-pin constructed according to my design.

The leading or characteristic feature of the design is the formation upon the two substantially parallel arms 1 1, of which the pin is made, of a series of corrugations 2 2, an eye

or loop 3 upon the outer end of one of said arms, and a larger substantially pear-shaped eye or loop 4 upon the end of the opposite of said arms, the said loop 4 being of larger dimensions than the loop 3. 20

What is claimed as the invention is—

The design for a clothes-pin, substantially as herein shown and described.

In testimony whereof I have signed this specification in the presence of two subscribing witnesses. 25

FREDERICK C. HAZEN.
